GAME

Elysia Florence van Santen, Chicago, Ill.

Application February 26, 1934, Serial No. 712,900

9 Claims. (Cl. 273—145)

My invention relates to an improvement in games and has for one purpose the provision of an improved game wherein counters or indicating members may be manually imparted a variety of 5 positions or accommodations. Other objects will appear from time to time in the course of the specification and drawing.

I illustrate my invention more or less diagrammatically in the accompanying drawing wherein—
10 Figure 1 is a plan view partly in section;
Figure 2 is a section on the line 2—2 of Figure 1;
Figure 3 is a section on the line 3—3 of Figure 2;
Figure 4 is a view similar to Figure 2 with parts in a different position; and
15 Figure 5 is a perspective view of one of the dice used.

Like parts are indicated by like symbols throughout the specification and drawing.

Referring to the drawing, I generally indicates 20 any suitable base made of any suitable material, which may, for example, be of wood or fiber. It may have a bottom pad 2 if desired, of rubber, felt or the like.

Mounted upon the base 1 is an upwardly extending pin 3 which may be screw threaded or otherwise secured at its lower edge to the base 1. Secured to its top is a platform or lateral extension 4, preferably flat on the top. It may have a lower ledge 5 if desired.

25 Slidably mounted upon the pin 3 is a tubular sleeve 6 with which is associated at its lower end, the horizontal platform 7, the tube being perfectly unitary or permanently secured together as shown.

30 In order to maintain the platform 7 normally in raised position, I may use any suitable yielding means. I illustrate, as one exemplification of such yielding means, a coil spring 8 which surrounds and is guided by the pin 3. It is effective 35 normally to thrust the sleeve 6 and the platform 7 as far up as they will go, the ledge 5 serving as an upper abutment. In order to impart a downward movement to the platform 7 I may employ any suitable connection but I illustrate herein as 40 a practical connection, a lever 9 pivoted as at 10 and provided with an outwardly extending tactal control member 11. 12 is any suitable connection between the lever 9 and the bottom of the platform 7 whereby, when the lever 11 is moved from the position in which it is shown in Figure 2 to the position in which it is shown in Figure 4, the platform 7 is depressed. If the operator suddenly releases the member 11, then the spring 8 45 is effective to impart a sharp upward movement

of the sleeve 6 on the platform 7 which is abruptly terminated by contact with the ledge 5.

Loosely positioned upon the platform 7 are a plurality of dice or counters or indicating members. I illustrate, for example, two conventional 5 dice 13 and 14 and a third 15 which has four blank sides and two indicating sides. Referring, for example, to this member as shown in Figure 2, one side is illustrated with a little devil which may, for example, be of red color. Another side of 10 the die is shown in Figure 5 at 16 and may, for example, be green. It will be realized that I do not wish to be precisely limited to any particular counting or indicating means.

Surrounding the platforms 4 and 7 limiting the 15 movement of the dice is a transparent dome 17. It may be provided with bottom lugs or flanges 18 through which may pass securing screws or other securing means 19. 20 represents any suitable washer or pads which may be helpful 20 in the event that glass is used. It will be understood that any suitable material may be used, for example, glass, or celluloid or bakelite. The dome 17 is further provided with a slot 21, 25 through which passes the lever 9.

It will be realized that whereas I have described and shown a practical and operative device, nevertheless many changes might be made in the size, shape, number and disposition of parts without departing from the spirit of my invention. I therefore wish my description and drawing to be taken as in a broad sense illustrative and diagrammatic rather than as limiting me to my specific showing.

The use and operation of my machine are as 35 follows:

The purpose of my game device is for the player to get a counter or counters positioned upon the platform 4. The game starts with the 40 counters or dice and one or more may be used upon the platform 7. The first player then imparts a sharp upward movement to the platform by pulling down on the member 11 and releasing it. The dome 17 limits the upward movement of the dice but does not impart any particular direction to such movement. The player, by gauging the length of movement or the rapidity of movement of the member 11 can, to a considerable extent control the sharpness of the upward movement of the member 7.

As an example of one game that can be played, the object may be to get a maximum number of 45 points in a predetermined number of movements of the member 11. These points may be added up from the side of the conventional dice. The die 50

15 may be employed in a variety of ways. For example, the red or green sides may have a pre-determined value. Or they may have a negative value. Or getting the die 15 on the top of the 5 platform may give an additional turn to the player.

I claim:

1. In a game device, a base, a fixed plane, horizontal surfaced platform associated with said 10 base, a movable platform associated with said base, and surrounding said fixed platform, means for imparting a sharp upward movement to the movable platform, a counter adapted normally to lie loosely upon said movable platform, the fixed 15 platform having an upper supporting surface of sufficient area to hold said counter in case it lands thereon, and a transparent housing surrounding the platforms, the diameter of said transparent housing being substantially greater 20 than the diameter of the fixed platform.

2. In a game device, a base, a fixed platform associated with said base, a movable platform associated with said base, means for imparting a sharp upward movement to the movable platform, a counter adapted normally to lie loosely upon said movable platform, the fixed platform having an upper supporting surface of sufficient area to hold said counter in case it lands thereon, and a transparent housing surrounding the 25 platforms, a stem upon which said fixed platform is mounted, said movable platform being guided upon said stem.

3. In a game device, a base, a fixed plane, horizontal surfaced platform associated with said 35 base, a movable platform associated with said base, and surrounding said fixed platform, yielding means tending normally to urge said movable platform to a predetermined upper position, manually operable means for depressing said platform 40 below said normal upper position and a counter upon said movable platform, the fixed platform having an upper supporting surface of sufficient area to hold said counter in case it lands thereon, said fixed platform being of substantially less diameter than said movable platform.

4. In a game device, a base, a fixed plane, horizontal surfaced platform associated with said 50 base, a movable platform associated with said base, and surrounding said fixed platform, means for imparting a sharp upward movement to the movable platform, a counter adapted normally to lie loosely upon said movable platform, the fixed platform having an upper supporting surface of sufficient area to hold said counter in case it lands thereon, said fixed platform being of substantially less diameter than said movable platform.

5. In a game device, a base, a fixed platform associated with said base, a movable platform associated with said base, means for imparting a sharp upward movement to the movable platform, a counter adapted normally to lie loosely upon said movable platform, the fixed platform having an upper supporting surface of sufficient 60 area to hold said counter in case it lands thereon, a pin upon which said fixed platform is mounted,

said movable platform being guided upon said pin.

6. In a game device, a base, a fixed plane, horizontal surfaced platform associated with said base, a movable platform associated with said base, and surrounding said fixed platform, means for imparting a sharp upward movement to the movable platform, including a spring positioned beneath said movable platform and means for depressing said platform against the resistance of said spring, a counter adapted normally to lie loosely upon said movable platform, the fixed platform having an upper supporting surface of sufficient area to hold said counter in case it lands thereon, said fixed platform being of substantially less diameter than said movable platform.

7. In a game device, a base, a fixed platform associated with said base, a movable platform associated with said base, means for imparting a sharp upward movement to the movable platform, a counter adapted normally to lie loosely upon said movable platform, the fixed platform having an upper supporting surface of sufficient area to hold said counter in case it lands thereon, a pin upon which said fixed platform is mounted, said movable platform being guided upon said pin, the means for imparting a sharp upward movement to the movable platform including a coil spring surrounded and guided upon said pin and means for depressing said platform against the resistance of said spring.

8. In a game device, a base, a fixed platform mounted on said base and positioned substantially thereabove and having a plane, horizontal surfaced counter supporting area, a movable platform associated with said base and of substantially greater diameter than the fixed platform, said movable platform extending outwardly beyond said fixed platform throughout the area of the fixed platform, means for imparting a sharp upward movement to the movable platform, and a counter adapted normally to lie loosely upon said movable platform.

9. In a game device, a base, a fixed platform mounted on said base and positioned substantially thereabove and having plane, horizontal surfaced counter supporting area, a movable platform associated with said base and of substantially greater diameter than the fixed platform, said movable platform extending outwardly beyond said fixed platform throughout the area of the fixed platform, means for imparting a sharp upward movement to the movable platform, and a counter adapted normally to lie loosely upon said movable platform, and a transparent housing surrounding both platforms and of an inside diameter approximately the exterior diameter of the movable platform, the counter supporting area of the fixed platform being substantially less than the counter supporting area of the movable platform, its edge being separated from the opposed portion of the transparent housing by a distance sufficient to permit the counter to pass about the edge of the fixed platform and reach the supporting area thereof.

ELYRIA FLORENCE VAN SANTEN.
